(57) **CLAIM**

I claim the ornamental design for a modular doll case, as shown.

DESCRIPTION

FIG. 1 is a front perspective view of the doll case of the present invention in a closed configuration;

FIG. 2 is a front elevational view of the doll case of FIG. 1;
FIG. 3 is a rear elevational view of the doll case of FIG. 1;
FIG. 4 is a right side elevational view of the doll case of FIG. 1;

FIG. 5 is a left side elevational view of the doll case of FIG. 1;

FIG. 6 is a top plan view of the doll case of FIG. 1;
FIG. 7 is a bottom plan view of the doll case of FIG. 1; and,
FIG. 8 is a perspective view showing the doll case of FIG. 1 in an open configuration with a transparent modular insert partially removed.
